UNITED STATES PATENT OFFICE.

WILLIAM C. PEET, OF NEW YORK, N. Y., ASSIGNOR TO THE J. L. MOTT IRON WORKS, OF SAME PLACE.

DESIGN FOR AN EARTHENWARE BATH-TUB.

SPECIFICATION forming part of Design No. 17,410, dated June 21, 1887.

Application filed May 14, 1887. Serial No. 238,273. Term of patent 7 years.

To all whom it may concern:

Be it known that I, WILLIAM C. PEET, of the city and State of New York, have invented a Design for Earthenware Bath-Tubs, of which 5 the following is a specification.

This design relates to the ornamental shape and configuration of the feet and the ornaments in relief upon the sides and rims in earthenware bath-tubs, as shown in the accompanying drawings, in which—

Figure 1 represents the bath-tub complete. Fig. 2 is a separate view in larger size of one of the feet. Fig. 3 is a separate view of the 15 ornamentation on the sides of the tub, and Fig. 4 is a separate view of the design upon the rim.

The design for the feet is composed of the scrolls *a* and *b* and diverging leaflets, as shown, the ornaments being on the two surfaces of 20 each foot and meeting at the corners.

The sides of the bath-tub are ornamented with molded panels, as shown at *d*, containing a row of cinque-foil ornaments, *c*, in relief, with intermediate leaflets, *i*. The top edges

of the bath-tub are ornamented with a rounding surface having transverse bands *k* and intermediate vine and leaves, as at *l*.

I claim—

1. In a design for an earthenware bath-tub, the design of the ornamentation of the feet, 30 consisting in the scrolls upon the two outer surfaces meeting at the corner, and diverging leaflets, substantially as represented.

2. In a design for an earthenware bath-tub, the design of the ornamentation of the sides, 35 consisting in the molded panel and the row of cinque-foil ornaments and leaflets, as represented.

3. In a design for an earthenware bath tub, the design of the ornamentation of the top 40 edge, consisting in the rounding surface with the transverse ribs and vine and leaflets, as represented.

Signed by me this 12th day of April, 1887.
WILLIAM C. PEET.
